UNITED STATES PATENT OFFICE.

LAURENCE J. BERKELEY, OF RACINE, WISCONSIN, ASSIGNOR TO THE P & M COMPANY,
OF CHICAGO, ILLINOIS, A CORPORATION OF ILLINOIS.

RAIL-ANCHOR.

1,301,219.

Specification of Letters Patent. Patented Apr. 22, 1919.

Application filed July 30, 1918. Serial No. 247,403.

To all whom it may concern:

Be it known that I, LAURENCE J. BERKELEY, a citizen of the United States, residing at Racine, in the county of Racine and State 5 of Wisconsin, have invented certain new and useful Improvements in Rail-Anchors, of which the following is a specification.

My invention relates to a rail anchor or anti-creeping device, and particularly to a 10 device adapted to engage with one flange only of the base of a rail and to be held in its operative position by means of a member which cuts or bites into the rail.

One of the principal objects of my invention is to provide an anti-creeping device of 15 this type which will be small, compact, inexpensive to manufacture, and capable of being easily applied to a rail, and which at the same time, will have the necessary 20 strength and tenacity of grip on the rail to withstand the very considerable stresses to which devices of this sort are subjected. More particularly my invention relates to an 25 anti-creep or rail anchor comprising a shoe member adapted to engage the rail on one side only, and a revoluble key for holding said shoe in locked engagement with the rail.

The device will be more readily understood 30 by reference to the accompanying drawings, wherein:

Figure 1 is a side elevation of a rail and 35 a portion of a tie, showing the rail anchor of my invention in position on the rail;

Fig. 2 is a plan view of the parts shown in Fig. 1;

Fig. 3 is a sectional view on the line 3—3 of Fig. 1;

Fig. 4 is a perspective view of the shoe 40 and rail-engaging member of the anchor; and

Fig. 5 is an enlarged perspective view of the key member.

In the drawings, the anchor is shown as 45 applied to one of the base flanges 10 of a rail 11 in position to abut a tie 12.

The anchor comprises a shoe consisting 50 preferably of a single malleable iron casting having upper and lower jaw members 13, 14, which define a space 15, shaped to accommodate one flange of the base of the rail. A depending shoulder or flange 16 serves as an abutment for the tie. The device is

strengthened by suitable ribs in the usual manner.

A groove 17, preferably of substantially triangular form in cross section, is provided in the lower jaw member 14, the groove being open throughout a portion of its length to the space 15. The groove also extends 60 through the end wall of the device and is adapted to receive a revoluble key 18, shown in detail in Fig. 5. The key is enlarged at one end to provide a head 19, the squared shoulder of which abuts the outer surface 65 of the metal surrounding the opening through the end wall of the shoe. Preferably the bottom edge 21 of the key is rounded to permit rotation of the key in the groove 17, the bottom of which is correspondingly rounded, as indicated at 22. The upper edge of the key is provided with a plurality of preferably diagonally disposed ribs or teeth 23, the number and size of which may be varied as may be necessary to 70 give the anchor sufficient holding capacity. Preferably, as will be noted by referring to Fig. 2, the slant of the teeth 23 is such that the key when rotated into locking position 75 will draw the anchor more tightly upon the 80 rail.

In locating the device on the rail flange the shoe is placed against the tie and forced into tight engagement with the flange by means of a hammer, for example. Thereupon the key is engaged by a suitable tool and rotated from the inclined position shown in the dotted lines in Fig. 1 to the substantially vertical position shown in the full lines in this and other figures of the drawings. This causes the teeth or ribs 23 to bite into the rail base. After the key has been turned to its locking or operative position, as described, it may be held in such position by 95 any suitable means. For example, the shoe may be provided with a lug 24, which lug is bent downwardly alongside of the key.

It is apparent that the exact form and arrangement of the parts are immaterial, and that changes may be made therein without departure from the principle of my invention.

I claim:

1. In a rail anchor, the combination of a rail engaging member provided with a part 105 adapted to bear against a tie, and a revo-

luble key adapted to bite into the rail for holding said member in locked engagement with the rail.

2. In a rail anchor, the combination of a rail engaging member provided with a part adapted to bear against a tie, and a revolute key, transversely arranged with respect to the rail, and adapted to bite into the same for holding said member in locked engagement with the rail.

3. In a rail anchor, the combination of a rail engaging member provided with a part adapted to bear against a tie, and formed with a groove, and a revolute key in said groove adapted to bite into the rail for holding said member in locked engagement with the rail.

4. In a rail anchor, the combination of a rail engaging member provided with means for bearing against a tie and comprising jaws to engage the top and bottom faces of the base flange of a rail, one of said jaws being formed with a key-way, and a revolute key in said key-way adapted to bite into the base of the rail for holding said member in locked engagement with the rail.

5. In a rail anchor, the combination of a rail engaging member provided with means for bearing against a tie and comprising jaws to engage the top and bottom faces of the base flange of a rail, one of said jaws being formed with a key-way transversely arranged with respect to the rail, and a revolute key in said key-way adapted to bite into the base of the rail for holding said member in locked engagement with the rail.

6. In a rail anchor, the combination of a rail engaging member provided with means for bearing against the tie and comprising upper and lower jaws to engage the top and bottom faces of the base flange of the rail, the lower jaw being formed with a key-way, and a revolute key in said key-way adapted to bite into the bottom of the base flange for holding said member in locked engagement with the rail.

7. In a rail anchor, the combination of a rail engaging member provided with means for bearing against a tie and comprising upper and lower jaws to engage the top and bottom faces of the base flange of the rail, the lower jaw being formed with a key-way, transversely-arranged with respect to the rail, and a revolute key in said key-way adapted to bite into the bottom of the base flange for holding said member in locked engagement with the rail.

8. In a rail anchor, the combination of a rail engaging member provided with a part adapted to bear against a tie, and a revolute key having a plurality of teeth adapted to bite into the rail for holding said member in locked engagement with the rail.

9. In a rail anchor, the combination of a rail engaging member provided with a part

adapted to bear against a tie, and a revolute key having a plurality of teeth, said teeth being diagonally arranged so that when the key is turned to its operative position the teeth tend to draw said rail engaging member into closer engagement with the rail. 70

10. In a rail anchor, the combination of a rail engaging member provided with a part adapted to bear against a tie, a revolute key adapted to bite into the rail for holding 75 said member in locked engagement with the rail, and means for holding said key in its operative position.

11. In a rail anchor, the combination of a rail engaging member provided with a part 80 adapted to bear against a tie, a revolute key adapted to bite into the rail for holding said member in locked engagement with the rail, and a lug on said rail engaging member adapted to be bent down behind the key to 85 hold the same in its operative position.

12. In a rail anchor for engaging one side of a rail only, the combination of a shoe adapted to have a wedging hold on one of the base flanges of the rail, said shoe being 90 formed with a key-way having a substantially vertical face and an inclined face, and a revolute key in said key-way provided with teeth which are adapted to bite into the base of the rail when the key is turned 95 against the vertical face of the key-way.

13. In a rail anchor for engaging one side of a rail only, the combination of a shoe adapted to have a wedging hold on one of the base flanges of the rail, said shoe being 100 formed with a key way, transversely arranged with respect to the rail, having a substantially vertical face and an inclined face, and a revolute key in said key-way provided with teeth which are adapted to 105 bite into the base of the rail when the key is turned against the vertical face of the key-way.

14. In a rail anchor for engaging one side of a rail only, the combination of a shoe 110 adapted to have a wedging hold on one of the base flanges of the rail, said shoe being formed with a key-way having a substantially vertical face and an inclined face, a revolute key in said key-way provided with 115 teeth which are adapted to bite into the base of the rail when the key is turned against the vertical face of the key-way, and means for holding said key against said vertical face. 120

15. In a rail anchor for engaging one side only of the base flange of a rail, the combination of a rail engaging member provided with means for bearing against a tie and comprising upper and lower jaws, the lower jaw being formed with a key-way rounded at the bottom and having a substantially vertical face and an inclined face, and a revolute key in said key-way, the bottom of which is rounded and the upper edge of 130

which is formed with ribs having cutting edges.

16. In a rail anchor for engaging one side only of the base flange of a rail, the combination of a rail engaging member provided with means for bearing against a tie and comprising upper and lower jaws, the lower jaw being formed with a key-way rounded at the bottom and having a substantially vertical face and an inclined face, and a revolute key in said key-way, the bottom of which is rounded and the upper edge of

which is formed with ribs having cutting edges which are disposed diagonally with respect to the rail.

17. In a rail anchor, the combination of a shoe recessed to engage one of the base flanges of a rail and formed with a key-way, and a revolute key in said key-way having a head bearing against the outer end of the 20 shoe and teeth adapted when the key is turned to its operative position to bite into the base of the rail.

LAURENCE J. BERKELEY.
